UNITED STATES PATENT OFFICE.

JOHN MEHL, JR., OF JERSEY CITY, NEW JERSEY.

DESIGN FOR A BELT-BODY.

SPECIFICATION forming part of Design No. 32,599, dated April 24, 1900.

Application filed March 27, 1900. Serial No. 10,402. Term of patent 3½ years.

To all whom it may concern.

Be it known that I, JOHN MEHL, Jr., a citizen of the United States, and a resident of Jersey City, in the county of Hudson and State of New Jersey, have invented and produced 5 a new and original Design for a Belt-Body, of which the following is a specification.

The essential feature of my design consists in a belt-body having its outer side embellished with ribs converging toward each other 10 as they extend in opposite directions from the middle portion of the back, and an intermediate rib turned to form oppositely-disposed loops at the back.

15 In the accompanying drawings, Figure 1 is an outside view of the belt-body, and Fig. 2 is a transverse section through the line 2 2 of Fig. 1.

The belt-body is denoted as a whole by

A. The ribs, which converge as they extend 20 in opposite directions from the back toward the ends, are denoted by B B'. The intermediate rib, developed into oppositely-extending loops at the back, is denoted by C C', the oppositely-arranged loops of the same being denoted by c c'. 25

What I claim is—

The design for a belt-body, substantially as herein shown and described.

In testimony that I claim the foregoing as 30 my invention I have signed my name, in presence of two witnesses, this 23d day of March, 1900.

JOHN MEHL, JR.
